UNITED STATES PATENT OFFICE.

ERNEST RICHARDSON, OF COLLEGE HILL BOROUGH, PENNSYLVANIA.

THERMOMETER.

1,423,257.

Specification of Letters Patent.

Patented July 18, 1922.

Application filed July 12, 1921. Serial No. 484,041.

To all whom it may concern:

Be it known that I, ERNEST RICHARDSON, a citizen of the United States, residing at College Hill Borough, Beaver County, and 5 State of Pennsylvania, have invented new and useful Improvements in Thermometers, of which the following is a specification.

My invention relates to thermometers in connection with suitable mountings therefor. The object of this invention is to provide for thermometers suitable mountings adapted to contain advertising matter.

Referring to the accompanying drawing, Fig. 1 is a front elevation of one form of 15 my invention; Fig. 2, an enlarged rear elevation of the lower part of Fig. 1; Fig. 3, a section on the line III—III of Fig. 2; Fig. 4, a similar section of a second form of my invention; and Fig. 5, an enlarged detail 20 of a part of Fig. 4.

On Figs. 1, 2, and 3 of the drawing, I show a stamped sheet-metal frame having the plane body 1, and the endless flange 2 around its edges. I arrange a thermometer 25 on the frame which has ample space for advertising matter as shown.

In a suitable opening in the body 1, I mount the outer end of the shaft 3, which carries the hand or pointer 4 which travels 30 over suitable temperature indicia on the outer face of the body. The rear end of the shaft 3 is mounted in the bracket 5 secured to the rear face of the body by the screws 6. A thermostatic coil or helix is mounted 35 between the body 1 and the bracket 5, one end of the helix being secured to the shaft 3 and the other end to the post 7 secured to the back of the body 1.

The pointer and the indicia are covered by 40 a suitable transparent cover glass 8 mounted on a spacing ring 9 resting against the outer face of the body 1. A sheet-metal casing 10 surrounds the ring 9 and has its outer end turned inwardly so as to engage the outer 45 face of the cover glass 8 and its inner end provided with tongues 11 which extend through holes 12 in the body 1 and are bent or clinched against the rear face of the body. The frame is preferably covered with a coat 50 of enamel 17.

In Figs. 4 and 5, I dispense with the separate spacing ring and provide in its place the annular shoulder 13 integral with the body 1^a. An annular bead 14 also integral 55 with the body 1 extends out in front of the

cover glass 8. This bead provides a seat for the sheet-metal ring 15 which has a U-shaped cross-section permitting it to fit the said bead and have its inner edge rest on the outer face of the cover glass. The ring may 60 be secured to the body 1^a in various ways, as by means of the bolts 16 which pass through the ring 15 and the bead and have their heads on the ring and their inner ends in the nuts 18 in the hollow side of the bead. 65

The frame may be supplied with ventilating openings of any type for admitting air to the interior of the frame. I have marked these openings 19.

I claim—

1. A thermometer comprising a sheet-metal frame with a marginal flange forming a hollow casing with the rear side open and having a round bearing-opening, a bracket 70 lying on the inner face of the frame and wholly within the same and having a bearing-opening in alinement with the other bearing-opening, means adjacent to the opening in the bracket for securing the latter to the frame, a shaft mounted in the said 75 openings, a pointer on the outer end of the shaft beyond the frame, there being temperature indicia on the outer face of the frame co-extensive with the range of the pointer, a thermostatic coil between the 80 frame and the bracket, having one end fixed and the other end attached to the shaft, a cover glass for the pointer, means spacing the glass from the pointer and indicia, and a ring attached to the frame and securing the 85 glass in fixed relation to the frame. 90

2. A thermometer comprising a sheet-metal frame with a marginal flange forming a hollow casing with the rear side open and having a round bearing-opening, a 95 bracket lying on the inner face of the frame and wholly within the same and having a bearing-opening in alinement with the other bearing-opening, means adjacent to the opening in the bracket for securing the latter to the frame, a shaft mounted in the said 100 openings, a pointer on the outer end of the shaft beyond the frame, there being temperature indicia on the outer face of the frame co-extensive with the range of the pointer, a thermostatic coil between the 105 frame and the bracket, having one end fixed and the other end attached to the shaft, a cover glass for the pointer, means integral with the frame for spacing the glass from 110

the pointer and indicia, and a ring attached to the frame and securing the glass in fixed relation to the frame.

3. A hollow stamped sheet-metal frame, 5 a bracket on the rear face thereof, a shaft mounted in the frame and the bracket, a pointer on the outer end of the shaft, there being temperature indicia on the frame co-extensive with the range of the pointer, a 10 thermostatic coil between the frame and the bracket, having one end fixed and the other

end attached to the shaft, a cover glass for the pointer, means integral with the frame for spacing the glass from the pointer and indicia, the frame having a bead projecting 15 in front of the glass, a ring on the bead and engaging the outer face of the glass, and means for securing the ring to the frame.

Signed at Pittsburgh, Penna., this 11th day of July, 1921.

ERNEST RICHARDSON.
